his Attorney.*

UNITED STATES PATENT OFFICE.

ARTHUR FRISCH, OF BROOKLYN, NEW YORK, ASSIGNOR, BY MESNE ASSIGNMENTS,
TO VOICES INCORPORATED, A CORPORATION OF DELAWARE.

SOUND-PRODUCING DEVICE.

Application filed February 11, 1922. Serial No. 535,737.

This invention relates to sound producing devices, particularly such as are adapted for use in connection with or for insertion in dolls or other toys.

5 The object of my improvements is to provide a device of the class described, simple in construction, having few parts easily assembled and when assembled having small liability to derangement. Other objects will 10 appear later herein.

In the drawings accompanying this specification there is illustrated one embodiment of my invention and which is at present the preferred embodiment thereof, for use in the 15 bodies of dolls. For other toys or other uses the device may be modified to meet particular environments and requirements, all within the scope of my invention.

Figure 1 is a vertical sectional elevation 20 on line 1, 1 of Fig. 2. Fig. 2 is a sectional plan view on line 2, 2 of Fig. 1. Figs. 3 and 4 are fragmentary plan views corresponding with a portion of what is shown in Fig. 2, and showing modified forms of some 25 details of my invention. The scale of all the figures of the drawing is the same.

Referring now particularly to Figs. 1 and 2 my improvements comprise a bellows 3, preferably of ordinary character with two 30 stiff walls 5, 6 articulated along their adjacent ends 5^a, 6^a, and having the usual flexible side and end walls 7 and 8, respectively. One wall, as 5, of said bellows may be secured to a fixed portion of the device 35 as wall 9 of a containing case 10 while the other bellows wall 6 is pivoted with respect thereto. Said casing 10 is preferably of general tubular form and in the form illustrated is substantially square in cross-section and comprises four walls 9, 11, 12 and 40 13, arranged to form a rectangular tube, and an end wall 14 closing in one end thereof. The other end of said tube or case is open except that it is preferably provided with a 45 covering 15 of cheese cloth or the like, the apertures through the cloth between the warp and woof threads thereof being adapted for permitting the passage of sound therethrough. Wall 6 of bellows 3, which is 50 herein shown as the movable wall, is preferably of metal and preferably carries integral therewith reed box 16 having the usual reed 17. Said reed box communicates with sound chamber 19 by passage 18. Said

sound chamber has an open end 20 preferably of rectangular form, and in the plan view of Fig. 2 the upper and lower walls of the mid portion of said open end 20 are cut back to form V seats at 20^a and 20^b. Across said open end, gate 21 is fixed at its 60 ends to the opposite side walls of chamber 19. Said chamber 19 may be provided with the usual nasal vent 22. Wall 6 of bellows 3, being preferably of metal, provides sufficient weight for closing the bellows when 65 the device is held with wall 5 approximately horizontal. Gate 21 is preferably of thin sheet material of yieldable character, such as rubber, and said gate is arranged to be closed at suitable times onto its V seats during the closing movement of the bellows, by means of arm 23 attached to some fixed portion of the device, herein illustrated as wall 70 13 of case 10. Said arm 23 is preferably arranged midway widthwise gate 21, see Fig. 75 2, and is provided with portions 23^a and 23^b adapted and arranged for successively engaging gate 21 as that gate is carried by wall 6 of the bellows from the dotted line position of Fig. 1 to the full line position thereof and further, as the bellows is completely collapsed. Between portions 23^a and 23^b of arm 23 is bent out portion 23^x and below portion 23^b is another bent out portion 23^y. Said portions 23^x and 23^y permit gate 21 to 80 85 retract away from opening 20 whereby the sound is permitted to issue.

In the modification of Fig. 3, end wall 24 of the V front of open end 20 is nearly vertical to the general plane of end 20, and the edge walls 25 thereof are inclined inwardly relatively to the plane of said end. In this modification, gate 21 is fixed at one 90 end only thereof to end 20 and in general parallelism therewith, and is adapted for 95 closing down onto edge walls 25 to close the aperture in end 20, when engaged by arm 23.

In the modification of Fig. 4, end 20 is 100 beveled off at one or both ends, contiguous to the opening therein and edge walls 24 are parallel with the bellows hinge. Gate 21 may be fixed to one of the beveled end portions of end 20 and extend outwardly 105 over the opening thereof in position to be closed against that end to close said opening upon encountering arm 23. The operation of my improved device will, it is believed, be

clearly understood from the above detailed description of its construction. The device in its protecting casing 10 is adapted to be inserted in the body of a doll with the bellows member 5 horizontal and the bellows member 6 on top or nearest the head of the doll and the portion 5^a toward the back of the doll. Then when the doll is laid on its back the weighty member 6 falls away from member 5 by gravity and when the doll is placed in upright position, the weight of bellows wall 6 will cause the bellows to close, whereby gate 21 will be first released from its seat as it passes portion 23^x of arm 23; then, upon encountering portion 23^b of said arm, said gate will be closed and upon passing portion 23^y of said arm the gate will again be released and open up from its seat, the device thereby emitting a succession of sounds. Or the casing with the device therein may be placed in the body of a doll with the member 5 arranged vertically therein when the doll is in upright position and with the end 15 uppermost and the member 6 nearest the back of the doll. Then when the doll is laid on its back the weighted member 6 of the bellows will act by gravity to distend the bellows and when the body of the doll is tilted forward the weighted member 6 will act by gravity to compress the bellows, and when the bellows is compressed the air therein is forced out past the air actuated sound producing means 17 which is carried with the pivoted movable wall 6, and the valve 21, also carried thereby, is acted upon by the control member 23, fixed with respect to the casing and member 5, to control the operation of the valve during the compression movement of member 6 and so interrupt the sound issuing from the sound producing means 17 through the sound chamber 19 causing the device to utter a sound like ma-ma or pa-pa. By enclosing the parts in a casing adapted to be inserted in a doll the parts are kept free of parts of the stuffing material and other foreign matter in the doll and the apertured end 15 while permitting the issuance of the sounds therethrough at the same time prevents such foreign material from getting in through this open part of the casing. Furthermore and what is quite important the bellows is not only compressed by gravity but is also distended by gravity and no mechanical connections from outside of the casing are necessary to operate the device. Since the device is free of all mechanical connections to other parts of the doll outside of the casing, it may be easily and conveniently placed in dolls of various types and sizes by the doll manufacturer and the device does not have to be differently constructed and designed for different types and sizes of dolls. The casing, by reason of the fact that there are no mechanical connections extending therethrough has no large apertures through which foreign matter may enter and it protects the mechanism of the device against injury both before it is inserted in the doll and also afterward. In the latter case it is especially important when used in the ordinary stuffed doll made of flexible fabric.

While I have described my improvements in great detail and with respect to a preferred form of the invention, I do not desire to be limited to the details or form described, since many changes and modifications may be made and the improvements embodied in widely different forms without departing from the spirit and scope of the invention in its broader aspects. Hence I desire to cover all modifications and forms coming within the language or scope of any one or more of the appended claims.

I claim:

1. The combination of a tubular casing adapted to be inserted in the body of a doll and partly open to provide for the issuance of sound therefrom, the open part being covered with apertured material which serves to keep out foreign material while permitting the issuance of sound therethrough, a bellows enclosed in said casing, said bellows having one wall fixed with respect to the casing and the opposite wall pivoted with respect thereto, said walls extending longitudinally of the casing, said pivoted wall being weighted and acting to both compress and distend said bellows solely by gravity and upon changing the position of the doll in which the device is inserted, air actuated sound producing means carried with said pivoted movable wall of the bellows, a valve also carried thereby for interrupting the sound from said sound producing means during one movement of the pivoted wall, and a control member fixed with respect to the casing and controlling the operation of said valve during said movement of said pivoted member.
2. The combination of a casing adapted to be inserted in the body of a doll and partly open to provide for the issuance of sound therefrom, the open part being covered with apertured material which serves to keep out foreign material while permitting the issuance of sound therethrough, a bellows enclosed in said casing, said bellows having one wall fixed with respect to the casing and the opposite wall pivoted with respect thereto, the said walls extending longitudinally of the casing, said pivoted wall being weighted and free of all mechanical connections to other parts of the doll outside of said casing and acting to both compress and distend said bellows solely by gravity and upon changing the position of the doll in which the device is inserted, air actuated sound producing means carried with said

pivoted movable wall of the bellows, and means for interrupting the sound from said sound producing means during one movement of the pivoted wall, including a control member fixed with respect to the casing.

3. The combination of a casing adapted to be inserted in the body of a doll and partly open to provide for the issuance of sound therefrom, the open part being covered with apertured material which serves to keep out foreign material while permitting the issuance of sound therethrough, a bellows enclosed in said casing, said bellows having one wall fixed with respect to the casing and the opposite wall pivoted with respect thereto, said walls extending longitudinally of the casing, said pivoted wall being weighted and acting to both compress and distend said bellows solely by gravity and upon changing the position of the doll in which the device is inserted, air actuated sound producing means fixed with respect to one wall of the bellows and means for interrupting the sound from said sound producing means including a control member fixed with respect to the other wall of the bellows.

4. A sound producing device having a bellows with a relatively fixed head and a relatively movable head, said heads being pivoted with respect to one another along one edge thereof, a weight carried by the movable head at the opposite edge thereof, whereby the bellows may be operated by gravity, said weight having a sound chamber therein and a passageway from said sound chamber to the interior of said bellows, a sound reed associated with said passageway whereby operation of the bellows may cause the reed to sound and the sound therefrom to issue into said sound chamber, said weight also having an opening from the sound chamber through which the sound is adapted to issue to the outside.

5. In a device of the character described the combination of a bellows having a movable wall, means comprising a weight for moving said movable wall when said device is moved from inoperative to operative position, air actuated sound producing means carried by said bellows, said movable wall having an opening provided with a V seat for the emission of sound, a resiliently held gate extending across said movable wall opening and attached to said movable wall, and means for closing said gate.

6. In a device of the character described the combination of a bellows having a movable wall, means comprising a weight for moving said movable wall when said device is moved from inoperative to operative position, air actuated sound producing means carried by said bellows, said movable wall having an opening provided with a V seat for the emission of sound, a resiliently held

gate extending across said movable wall opening and attached at the V ends of said seat, and means for closing said gate.

7. In a device of the character described the combination of a bellows having a movable wall, means comprising a weight for moving said movable wall when said device is moved from inoperative to operative position, air actuated sound producing means carried by said bellows, said movable wall having an opening in the free end thereof for the emission of sound, a resiliently held gate extending across said movable wall opening and attached to said movable wall, and a fixed arm for coaction with said gate, said arm having a gate engaging profile adapted for alternately closing and releasing said gate.

8. A sound producing device having in combination a bellows, a sound reed connected to be operated thereby, means including a member having an opening through which the sound from the reed is adapted to issue, a valve member of resilient flexible material for closing and opening said opening whereby when the valve member is in open position sound may issue and when the valve member is in closed position the sound is muffled, said valve member being moved to one of said positions by the resiliency of the material of the valve member, and means acting to move said valve member to the other position responsive to the operation of the bellows.

9. A sound producing device having in combination an air chamber with a relatively fixed head, a head movable toward and from the fixed head, a sound reed operated by air forced thereby by movement of the movable head with respect to the fixed head, and means for interrupting the sound from said reed comprising a member having an opening through which the sound from the reed is adapted to issue, a valve member of resilient flexible material for closing and opening said opening whereby when the valve member is in open position sound may issue and when the valve member is in closed position the sound is muffled, said valve member being moved to one of said positions by the resiliency of the material of the valve member, and means acting to move said valve member to the other position responsive to the movement of the movable head with respect to the fixed head.

10. A sound producing device having in combination a bellows, a sound reed connected to be operated thereby, means including a member having an opening through which the sound from the reed is adapted to issue, a valve member of resilient flexible material for closing said opening, said valve member being normally maintained in open position by the resiliency of the valve member itself, and means automatically moving

the valve member to close said opening responsive to the operation of the bellows.

11. A sound producing device having a bellows with a relatively fixed head and a relatively movable head, said heads being pivoted with respect to one another along one edge thereof, a weight carried by the movable head at the opposite edge thereof, whereby the bellows may be operated by gravity, said weight having a sound chamber therein and a passageway from said sound chamber to the interior of said bellows, a sound reed associated with said passageway whereby operation of the bellows may cause the reed to sound and the sound therefrom to issue into said sound chamber, said weight also having an opening from the sound chamber through which the sound is adapted to issue to the outside and means for interrupting the sound from said opening including means for automatically closing said opening responsive to the operation of the bellows.

12. A sound producing device having a bellows with a relatively fixed head and a relatively movable head, said heads being pivoted with respect to one another along one edge thereof, a weight carried by the movable head at the opposite edge thereof, whereby the bellows may be operated by gravity, said weight having a sound chamber therein and a passageway from said sound chamber to the interior of said bellows, a sound reed associated with said passageway whereby operation of the bellows may cause the reed to sound and the sound therefrom to issue into said sound chamber, said weight also having an opening from the sound chamber through which the sound is adapted to issue to the outside and means for interrupting the sound from said opening including a valve member carried by the weighted head and adapted to open and close said opening and means carried by the other head for automatically controlling the operation of said valve member responsive to the operation of the bellows.

13. The combination of a tubular casing adapted to be inserted in the body of a doll and partly open to provide for the issuance of sound therefrom, the open part being covered with apertured material which serves to keep out foreign material while permitting the issuance of sound therethrough, a bellows enclosed in said casing, said bellows having one wall fixed with respect to the casing and the opposite wall pivoted with respect thereto along one edge of said walls, a weight carried by said movable pivoted wall at the opposite edge thereof whereby the bellows may be operated by gravity, said walls extending longitudinally of the casing, said weight having a sound chamber therein and a passageway, from having an opening from the sound chamber

bellows, a sound reed associated with said passageway, said weight also having an opening from the sound chamber through which the sound from the reed is adapted to issue to the outside, and means for interrupting the sound from said sound opening including a valve member carried by the weighted wall and adapted to open and close said opening, and means carried by the other wall and controlling the operation of said valve member responsive to the operation of the bellows.

14. A sound producing device having a bellows with a relatively fixed head and a relatively movable head, said heads being pivoted with respect to one another along one edge thereof, a weight carried by the movable head at the opposite edge thereof, whereby the bellows may be operated by gravity, said weight having a sound chamber therein and a passageway from said sound chamber to the interior of said bellows, a sound reed associated with said passageway whereby operation of the bellows may cause the reed to sound and the sound therefrom to issue into said sound chamber, said weight also having an opening from the sound chamber through which the sound is adapted to issue to the outside, said opening being in that face of the weight which is opposite from said pivotal edge, and means for interrupting the sound from said opening including means for automatically closing said opening responsive to the operation of the bellows.

15. A sound producing device having in combination a bellows having a relatively fixed head and a head movable toward and from the fixed head to compress and distend the bellows, said movable head comprising a metallic weight, whereby the bellows may be operated by gravity, said weight having a sound chamber therein and a passageway leading from said sound chamber to the interior of the bellows, a sound reed associated with said passageway, said weight also having an opening from the sound chamber through which the sound from the reed may issue to the outside and means for interrupting the sound from said opening including means for automatically closing said opening responsive to the operation of the bellows.

16. A sound producing device having in combination a bellows having a relatively fixed head and a head movable toward and from the fixed head to compress and distend the bellows, said movable head comprising a metallic weight whereby the bellows may be operated by gravity, said weight having a sound chamber therein and a passageway leading from said sound chamber to the interior of the bellows, a sound reed associated with said passageway, said weight also having an opening from the sound chamber

- through which the sound from the reed may issue to the outside, and means for interrupting the sound from said opening including a valve member carried by the 5 weighted head and adapted to open and close said opening, and means carried by the other head for automatically controlling the operation of said valve member responsive to the operation of the bellows.
- 10 17. A sound producing device having in combination a bellows having a relatively fixed head and a head movable toward and from the fixed head to compress and distend the bellows, said movable head comprising a metallic weight whereby the bellows may be operated by gravity, said weight having a sound chamber therein and a passageway leading from said sound chamber to the interior of the bellows, a sound reed associated with said passageway, said weight also having an opening from the sound chamber through which the sound from the reed may issue to the outside, said opening being in one of the side edges of said weight, and means for automatically closing and opening said opening responsive to the operation of the bellows. 40
- 15 18. A sound producing device having in combination a bellows having a relatively fixed head and a head movable toward and from the fixed head to compress and distend the bellows, said movable head comprising a metallic weight, whereby the bellows may be operated by gravity, said weight having a sound chamber therein and a passageway leading from said sound chamber to the interior of the bellows, and a sound reed associated with said passageway, said weight also having an opening from the sound chamber through which the sound from the reed may issue to the outside. 45
- 20 19. A sound producing device having in combination a bellows having a relatively fixed head and a head movable toward and from the fixed head to compress and distend the bellows, said movable head comprising a metallic weight whereby the bellows may be operated by gravity, said weight having a sound chamber therein and a passageway leading from said sound chamber to the interior of the bellows, and a sound reed associated with said passageway, said weight also having an opening from the sound chamber through which the sound from the reed may issue to the outside. 50

In witness whereof, I hereby affix my signature this 10th day of February, 1922.

ARTHUR FRISCH.

Certificate of Correction.

It is hereby certified that in Letters Patent No. 1,609,082, granted November 30, 1926, upon the application of Arthur Frisch, of Brooklyn, New York, for an improvement in "Sound-Producing Devices," an error appears in the printed specification requiring correction as follows: Page 4, line 65, for the words "having an opening from the sound chamber" read *said sound chamber to the interior of the*; and that the said Letters Patent should be read with this correction therein that the same may conform to the record of the case in the Patent Office.

Signed and sealed this 1st day of February, A. D. 1927.

[SEAL.]

M. J. MOORE,
Acting Commissioner of Patents.
